TOOL FOR CHIPPING CARBON DEPOSITS

Ralph C. Steider, Boise, Idaho

Application November 28, 1955, Serial No. 549,329

4 Claims. (Cl. 15—89)

The present invention relates to improvements in a tool for chipping carbon deposits from automotive parts such as valves and the like.

In automotive repairs work the mechanic is frequently called upon to remove carbon deposits from engine parts. The intake and exhaust valves of automobile engines in particular are susceptible to considerable carbon incrustation, and must be cleaned. The common practice in cleaning these members is to strike two of them together until the carbon deposits are loosened, and then buff them clean on a wire brush attachment to a bench grinder. While this method of cleaning does suffice to clean the valves, it takes considerable time, especially when hard deposits are present. Frequently many blows are required to loosen such hard deposits and much time is consumed.

It is the purpose of this invention to provide a tool which may be attached to a rotating shaft and which has a plurality of chipping surfaces adapted to strike repeated blows to loosen carbon deposits from objects held thereagainst.

More specifically it is the purpose to provide such a tool which may be threaded onto the rotating shaft of a bench grinder and which has such chipping surfaces adapted to loosen carbon deposits from automotive parts such as intake and exhaust valves.

The nature and advantages of my invention will appear more clearly from the following description and the accompanying drawings, wherein a preferred form of the invention is shown. It should be understood, however, that the drawings and description are illustrative only and are not intended to limit the invention, except insofar as it is limited by the claims.

In the drawings:

Figure 1 is a perspective view of the invention;

Figure 2 is an end view of the tool shown in Figure 1;

Figure 3 is a sectional view taken on the line 3—3 of Figure 2;

Figure 4 is a view illustrating the tool as mounted on a bench grinder; and

Figure 5 is a fragmentary view illustrating the tool in use.

Referring now to the drawings, and to Figures 1, 2 and 3 in particular, my improved carbon chipping tool, generally indicated by the numeral 10 comprises a cylindrical metal shaft 11 having an enlarged connecting head 12 formed at one end thereof. The connecting head 12, as shown in Figure 3, has a threaded aperture 13 therein extending axially of the shaft 11. The aperture 13 is adapted to receive the threaded end of a rotatable shaft as described later herein.

The shaft 11 has an enlarged portion 14 thereon near the head 12 whereby to provide a shoulder 15. A chipping member 16 is mounted on the shaft 11 and seats against the shoulder 15. The chipping member is non-slidably and non-rotatably mounted by means of a set screw 17. As shown in Figures 1 and 2 the chipping member 16 is hexagonal in cross section, having six plane surfaces 18 which meet in sharp edges 19. The edges

19 extend from one face of the member 16 to the opposite face, to provide sharp corners 20. It may be seen that upon rotation of the tool 10, the edges 19 and corners 20 will strike repeated blows at objects held thereagainst. 5 While the member 16 is shown as hexagonal in the drawings, it should be understood that other polygonal configurations would suffice, including a triangle, square, pentagon, etc. However, polygonal shapes having a large number of sides, as for example a twelve or fourteen sided polygon, are not practical, since the meeting edges of the plane surfaces in such figures are not spaced radially outward from the plane surfaces a sufficient distance to cause upon rotation, appreciable jarring of an object held against the surfaces.

In order to provide a second chipping member on the tool 10, the free end of the shaft 11 is formed as a tapered hexagonal chipping bit indicated at 21 in the drawings. The tapered hexagonal bit 21 is formed by cutting six converging plane surfaces 22 at the free end of the shaft 11. The surfaces 22 meet in sharp edges 23 which, upon rotation of the tool 10, will strike blows on an object held thereagainst.

As may be seen in the drawings, the two chipping members 16 and 21 are spaced a considerable distance apart, so that a valve held against one of the surfaces won't engage the other surface accidentally. The length of shaft 11 between the two chipping members is cylindrical, so that valves being cleaned by the member 16 and accidentally allowed to contact the shaft 11 will not be struck and damaged by engagement with the shaft 11, as would be the case if the shaft 11 were polygonal in cross section.

As hereinbefore described, in cleaning carbon incrusted valves the hard carbon deposits must first be chipped loose, and then the valves buffed clean. The buffing is usually accomplished with a circular wire brush attachment on a standard bench grinder. Such a grinder is shown at 24 in Figure 4. The wire brush attachment is indicated at 25. I have found it very convenient to mount my improved chipping tool 10 on the shaft of the grinder 24 adjacent the brush 25. The tool 10 may be so mounted by removing the nut which normally holds the brush 25 on the shaft, and replacing it with the tool 10. In this way the tool 10 is mounted for rotation in close proximity to the wire brush 25 so that the two may be used 45 together for cleaning carbon incrusted valves.

The method of using the tool 10 is illustrated in Figures 4 and 5. The valve, indicated at 26 is grasped by the stem, and the incrusted portions held against either of the whirling chipping members 16 or 21. The whirling projecting edges 19 or 23 strike repeated blows on the carbon deposits to loosen them. As may be seen from the drawings, the member 16 and the bit 21 provide chipping surfaces which are capable of reaching all parts of the valves 26.

55 It is believed that the nature and advantages of the invention appear clearly from the foregoing description.

Having thus described the invention, I claim:

1. A tool for chipping carbon deposits from articles such as valves of internal combustion engines comprising 60 a connecting head having means for securing said head to a rotating shaft, a rigid shaft portion secured to said connecting head and extending axially of the rotating shaft upon which the head is secured, said shaft portion having a chipping member thereon intermediate the head and the free end of the shaft portion, said chipping member being polygonal in cross section whereby to provide a plurality of projecting edges on its surface operable to strike repeated blows upon objects held thereagainst when the tool is rotated, said shaft portion having a polygonal end portion at the free end thereof whereby to provide 65 projecting edges thereon operable to strike blows to objects held thereagainst when the tool is rotated, and said 70

polygonal end portion being spaced from the chipping member, the portion of the shaft between the polygonal end portion and the chipping member being cylindrical whereby to allow objects to make contact therewith without being struck by sharp corners.

2. A tool for chipping carbon deposits from articles such as valves of internal combustion engines comprising a rigid cylindrical shaft, an enlarged head portion on said shaft, said head portion having a central aperture therein extending axially of the shaft, whereby to mount the tool for rotation about the axis of the shaft, a chipping member fixedly secured on said shaft, said chipping member being polygonal in cross section whereby to provide a plurality of projecting edges on its surface operable to strike repeated blows upon objects held thereagainst when the tool is rotated, said shaft having a tapered polygonal end portion thereon, said end portion being formed of a plurality of converging plane surfaces intersecting each other in sharp edges, said sharp edges operable to strike repeated blows upon objects held thereagainst when the tool is rotated, and said end portion being spaced from the chipping member.

3. A tool for chipping carbon deposits from articles such as valves of internal combustion engines comprising a rigid cylindrical shaft, an enlarged head portion on said shaft, said head portion having a central aperture therein extending axially of the shaft, whereby to mount the tool for rotation about the axis of the shaft, a chipping member fixedly secured on said shaft, said chipping member being hexagonal in cross section whereby to provide a plurality of projecting edges on its surface operable to strike

repeated blows upon objects held thereagainst when the tool is rotated, said shaft having a tapered hexagonal end portion thereon, said end portion being formed of a plurality of converging plane surfaces intersecting each other in sharp edges, said sharp edges operable to strike repeated blows upon objects held thereagainst when the tool is rotated, and said end portion being spaced from the chipping member.

4. A tool for chipping carbon deposits from articles such as valves of internal combustion engines comprising a connecting head having means for securing said head to a rotating shaft, a rigid shaft portion secured to said connecting head and extending axially of the rotating shaft upon which the head is secured, said shaft portion having a chipping member thereon intermediate the head and the free end of the shaft portion, said chipping member being polygonal in cross section whereby to provide a plurality of projecting edges on its surface operable to strike repeated blows upon objects held thereagainst when the tool is rotated, said shaft portion having a polygonal end portion at the free end thereof whereby to provide projecting edges thereon operable to strike blows to objects held thereagainst when the tool is rotated, and said polygonal end portion being spaced from the chipping member.
